[57] CLAIM

The ornamental design for a faucet, as shown and described.

DESCRIPTION

FIG. 1 is a left, top, front perspective view of a faucet embodying my new design;

FIG. 2 is a left side elevational view thereof, the right side elevational view being a mirror image of the left side shown;

FIG. 3 is a front elevational view thereof;

FIG. 4 is a top plan view thereof;

FIG. 5 is a rear elevational view thereof; and,

FIG. 6 is a bottom plan view thereof.

The broken line representations of holes in FIGS. 1, 4, and 5, and of mounting structure in FIGS. 1-3, 5, and 6, are for the purposes of illustration only, and form no part of the claimed design.
